UNITED STATES PATENT OFFICE.

PHILIP J. SAULSON, OF NEW YORK, N. Y., ASSIGNOR TO BEVERAGE MACHINE & BOTTLE COMPANY, INC., A CORPORATION OF NEW YORK.

FILLING-MACHINE.

1,171,356.

Specification of Letters Patent.

Patented Feb. 8, 1916.

Application filed October 29, 1914. Serial No. 869,344.

To all whom it may concern:

Be it known that I, PHILIP J. SAULSON, a citizen of the United States, residing in the borough of Manhattan of the city of 5 New York, in the county of New York, in the State of New York, have invented certain new and useful Improvements in Filling-Machines, of which the following is a specification, reference being had to the accompanying drawings, which form a part 10 hereof.

This invention relates to machines for filling bottles, siphons and other receptacles with any liquid, whether charged with gas 15 or not, under pressure and out of contact with atmospheric air.

The improved machine is designed especially for the filling, with a gas charged liquid, such as beer or any other foaming beverage, siphons or similar receptacles in which liquid is kept under pressure of carbonic acid gas. It is designed especially for the filling of receptacles of this character which are provided with gas vents or safety 25 valves which permit the escape of gas when the pressure exceeds a predetermined degree but otherwise act to retain the liquid under a pressure lower than that at which the vents open.

One object of the invention is to enable 30 the filling of such receptacles to be carried on rapidly and automatically, that is, without further attention on the part of the attendant than that involved in the re- 35 placing of filled receptacles by empty receptacles.

Another object is to permit the filling to be carried on at all times under gas pressure and without danger of contamination 40 of the liquid by contact with atmospheric air.

Still another object is to permit a measured quantity of liquid to be introduced into each receptacle regardless of its greater capacity.

It is also an object to provide for the introduction into each receptacle of a measured quantity of syrup or extract to be mixed in the receptacle with the main body 50 of the liquid with which it is filled.

Other objects and accomplishments of the invention will appear as this description proceeds.

In the drawings, in which embodiments of

the invention are illustrated—Figure 1 is a 55 view in side elevation, partly broken out or in vertical section, of a filling machine which embodies the invention. Fig. 2 is a view of the same in front elevation, the siphon shown in Fig. 1 being removed. Fig. 60 3 is a top view of the same, the siphon being shown in position. Fig. 4 is a detail view of one of the controlling valves. Fig. 5 is a schematic view showing, more clearly than in the other figures of the drawings, some of 65 the parts of the machine in their operative relations but not in the true relations which they occupy in the machine. Fig. 6 is a detail view of the vent or safety valve applied to the receptacle to be filled. Figs. 7 70 and 8 are detail views of the gas and liquid controlling valves. Figs. 9, 10 and 11 are detail views illustrating a modified form of the gas and liquid controlling valves and their operating devices, the right hand portion 75 of Fig. 9 being in section on the plane indicated by the line 9—9 of Fig. 10 and Fig. 11 being in section on the plane indicated by the line 11—11 of Fig. 10. Fig. 12 is a partial view in front elevation illustrating 80 a form of the apparatus similar to that shown in Figs. 1, 2 and 3, but with valves of the same character as those shown in Figs. 9, 10 and 11 and with the addition of a device for adding syrup or extract. Figs. 13 85 and 14 are detail views of one of the valves shown in Fig. 12, Fig. 14 being in section on the plane indicated by the line 14—14 of Fig. 13. Fig. 15 is a detail view of a portion 90 of the device for adding syrup or extract. Fig. 16 is a detail view, on a larger scale, of the valve controlling mechanism shown in Figs. 1, 2 and 3. Fig. 17 is a detail view 95 of the dash-pot shown in Fig. 16. Fig. 18 is a detail view of the valve connections and Fig. 12.

The machine illustrated in the accompanying drawings as an embodiment of the invention is designed particularly for the 100 filling of siphons, that is, receptacles in which the liquid, beer or charged water or any other effervescent or gas-charged liquid is held under gas pressure and from which it is discharged by gas pressure within the 105 container. Such a receptacle or container is indicated at A in Figs. 1, 3 and 5, the same comprising a liquid container a provided

with a vent or safety valve a' , which may be of ordinary construction, as shown in detail in Fig. 6, being adapted to open at a predetermined pressure, a gas container a^2 in which gas, usually carbonic acid gas, is stored under pressure to be admitted through a valve a^3 to the interior of the liquid container a from time to time as the liquid is withdrawn therefrom, a discharge pipe a^4 terminating in a suitable discharge nozzle a^5 , and a discharge valve a^6 . This vessel is designed to be filled through the discharge nozzle a^5 , the valve a^6 being then held open, while the displaced air or gas is discharged through the safety valve or vent a' . Such a vessel to be filled is placed upon a support b carried by a bracket arm b' which is secured to the frame B of the machine and the discharge nozzle a^5 is adapted to enter and fit snugly in the terminal c^x of a filling pipe hereinafter referred to, such terminal being provided with suitable packing devices for the purpose of making a tight joint. In the machine shown in Figs. 1-5 the horizontal portion of the discharge pipe a^4 a^5 serves to hold a portion of the mechanism in position for filling as hereinafter explained, the movement of such part to filling position being effected directly by the hand of the operator or by the placing of the siphon in position to be filled.

The beer or other liquid to be bottled may be supplied from any suitable source, such as the barrel or keg indicated (though not in true relative size) at C in Fig. 5. The gas under pressure of which the operation is carried on, may also be supplied from any suitable source such as the ordinary commercial carbonic acid gas cylinder C' , the flow of gas being controlled by suitable reducing valves c and c' . The gas, at reduced pressure, is admitted through a pipe c^2 to the closed supply vessel C and under its pressure the liquid is discharged through a pipe c^3 c^4 , provided with suitable stop cocks, to the filling machine. Preferably the liquid enters first a foam separating and equalizing chamber c^5 , which is common to all of the filling heads of a machine which may comprise many separate filling heads but is shown in the drawings as having only one. From the equalizing chamber c^5 the liquid is conducted through a pipe c^6 , a valve D , the construction of which will be explained, one member of a T-connection c^7 to a pipe c^8 to the measuring vessel E , the details of which will be described. The measured quantity of liquid received in the measuring vessel E is discharged therefrom under gas pressure, as hereinafter described, through the pipe c^8 and the other member of the T-connection c^7 and through a valve D' , the construction of which will be explained, to the discharge pipe c^9 and its terminal c^x . It will be understood that when the valve D is

opened the valve D' is closed and vice versa, the valves being controlled as hereinafter explained.

Gas is supplied from the common source through a pipe c^{11} , a gas valve F' , the construction and operation of which are hereinafter explained, a pipe c^{12} and a controlling valve G to the measuring vessel E . The gas displaced from the measuring vessel E , by the incoming liquid, is conducted through a pipe c^{13} , a gas valve F , the construction of which is similar to that of the valve F' , and a pipe c^{14} to the filling terminal c^x from which it enters the receptacle A , preceding the liquid. The valves F F' are controlled, as hereinafter explained, so that they open in alternation and in proper relation to the opening of the valves D and D' . The regulating valve G is suitably constructed, as shown in detail in Fig. 4, so as to permit the gas to enter the measuring vessel E slowly, in order to prevent the liquid from being driven out of the measuring vessel too violently. As shown in Fig. 4 this regulating valve comprises an ordinary needle valve g provided with a hand wheel g' by means of which the valve can be regulated closely.

The two valves D and D' may be identical in construction and a description of one will therefore suffice for both. As shown in Fig. 7 the valve D may comprise a block d having also a passage d^3 with which the pipe c^7 communicates and a valve seat d^2 , and having also a passage d^3 with which the pipe c^7 communicates, such passage terminating in an annular groove d^4 around the valve seat d^2 . A diaphragm valve d^5 , held in place by a cap d^6 , is pressed normally by a spring-pressed plunger d^7 against the valve seat d^2 , so that normally the passage through the valve is closed. The valve is opened at the proper time by means to be described.

The valves F and F' are also identical in construction and a description of one will suffice for both. The construction is substantially like that of the valves D and D' . The valve block f is provided with a central bore f' which communicates with the pipe c^{11} and has at its upper end a valve seat f^2 . It is also provided with a passage f^3 which communicates at its lower end with a pipe c^{12} and at its upper end with an annular groove f^4 which surrounds the valve seat f^2 . A diaphragm valve f^5 , held in place by a cap f^6 , is pressed normally by a spring-pressed plunger f^7 against the valve seat f^2 to close the passage through the valve. The valve is opened at the proper time by means to be described.

The measuring vessel E , which is preferably employed, comprises a tank e of suitable capacity which is mounted on the frame B of the machine and is connected through the pipe c^8 and the valve D with the supply

vessel C and through the pipe c^8 and the valve D' with the filling terminal e^8 ; as shown in Fig. 1 it is provided at its lower end, at the point of connection with the 5 pipe c^8 , with a valve seat e^1 which is closed, when the vessel e is empty, by a valve e^2 which is carried by a float e^3 . So long as there is any appreciable quantity of liquid 10 in the vessel e the float e^3 holds the valve e^2 from its seat so that the inflow and outflow of liquid may take place, but when the vessel e is empty of liquid the valve e^2 rests on its seat so as to prevent the outflow of gas. In the vessel e is a float e^4 which, through 15 suitable intermediate mechanism, such as that about to be described, controls the liquid and gas valves D D' and F F', as explained hereinafter. The stem e^5 of the float is connected, by a pin and slot connection e^6 , with a lever e^7 , pivotally mounted on a plate e^8 which is secured to a standard e^9 on the top of the vessel e. The lever e^7 is connected by a link e^{10} with a lever e^{11} which is pivoted to the main frame B as at 20 e^{12} . The lever e^{11} underlies a transverse pin or finger e^{13} (see particularly Figs. 1, 2 and 16) of one arm e^{14} secured to a shaft H. The latter is pivotally supported by a double lever or frame h which carries at its 25 forward end a cross-bar h' , by which the forward end of the lever may be pressed down either by the hand of the operator or by direct contact with the nozzle of the siphon, when the siphon is applied to the machine, and held down thereby, as indicated in Figs. 1 and 5. The lever or frame h is secured to the short shaft h^2 which is mounted in suitable bearings h^3 and has secured thereto a weighted arm h^4 by which 30 the lever is held normally but yieldingly with its forward end elevated. The shaft H, has secured thereto a hook h^5 which engages, when the parts are in the filling position, a pin i carried by an arm i' of a shaft i^2 . Another arm i^3 at one end of the shaft is pivotally connected with a link i^4 , forming therewith a toggle lever. The link i^4 is pivotally connected with a forked lever i^5 which is pivotally mounted on a standard i^6 and underlies the cross-head d^8 of the 35 plunger d^7 of the valve D. The arm i^3 is also pivotally connected by a link i^6 (forming therewith a toggle) with a forked lever i^7 which is pivoted on a standard i^8 and underlies the cross-head d^8 of the plunger d^7 of the valve D'. A similar arm i^{8x} , near the other end of the shaft i^2 (see Fig. 3), is similarly connected by a link i^{8x} with a forked lever i^{8x} which underlies the cross-head f^8 on the plunger f^7 of the valve F, and is 40 also connected by a link i^{8x} with a forked lever i^{8x} , which underlies the cross-head f^8 of the valve F'. A third arm i^{81} on the shaft i^2 is connected to the plunger h (see 45 Figs. 1, 3 and 16) of a dash-pot K which

is suitably supported on the frame B. A spring k' , within the cylinder k^2 of the dash-pot, acts upon the plunger h to move the connected parts, when they are released by the hook h^5 , from the positions shown by 50 full lines in Fig. 16 to the positions shown by dotted lines. When the parts are in the positions shown by full lines the valves D and F are held open against the tendency of the spring-pressed plungers d^7 to close 55 them and the valves D' and F' are permitted to be closed by their spring-pressed plungers. When the hook h^5 is disengaged from the arm i' and the spring k' is permitted to act the valves D and F are 60 permitted to be closed by their spring-pressed plungers and the valves D' and F' are opened. The disengagement of the hook h^5 is effected, when the measured quantity of liquid has been introduced into the measuring vessel E, by the lift of the float e^4 to its highest position, such lost movement in the connections being provided for as causes the float to act as it reaches the limit of its upward movement. It is of course possible 65 to vary the quantity of liquid which causes the float to act through adjustment of the connecting links in an obvious manner. As soon as the siphon is removed from the filling position the weighted arm h^4 causes the 70 frame h to be swung upward, carrying with it the shaft H, so that the hook h^5 rises into position to engage and does at once engage again the pin i of the arm i' , so that when the forward end of the lever h is pressed 75 down by the operator or by the weight of the siphon to be filled, the movements of the parts are reversed, against the action of the spring k' , and the valves D and F are 80 opened while the valves D' and F' are 85 closed.

The operation of the particular embodiment of the invention thus far described will now be understood readily by reference to Fig. 5: When the siphon is placed in position to be filled the lever h is swung downward, carrying the connected parts into the 90 positions shown in Fig. 16, in which the valves D and F are opened and the valves D' and F' are closed. Under the pressure 95 of the gas in the supply vessel C, the liquid therein therefore flows through the pipes c^4 , the foam separating and equalizing vessel c^5 , the pipe c^6 , the valve D and the pipe c^8 into the measuring vessel E. The gas (or, in the 100 first operation, the air) which is displaced by the liquid which enters the measuring vessel E, is forced out through the pipe c^{13} , the valve F and the pipe c^{14} into the siphon A, displacing therein the air (or gas) with 105 which the siphon was previously filled, such air (or gas) escaping through the safety valve a' . As soon as the predetermined 110 quantity of liquid has entered the measuring vessel E and the float e^4 has reached its high- 115

est point, the latch h^5 is disengaged from the arm i' and the spring k' is permitted to shift the connected links from the positions shown by the full lines in Fig. 16 to the positions shown by dotted lines therein, thus closing the valve D so as to stop the further flow of liquid into the measuring vessel, and also closing the valve F so as to prevent the further escape of gas from the top of the measuring vessel E. At the same time the valve F' is opened, which permits gas to flow from the gas supplied through the pipe c^{11} and the pipe c^{12} into the top of the measuring vessel E and the valve D' is opened so as to permit the measured quantity of liquid in the measuring vessel E to be forced by the gas pressure on the surface thereof through the pipe c^8 and the pipe c^9 into the siphon A. In the first operation of the machine the measuring vessel E and its connections contain atmospheric air and the first filling of liquid, which is used to expel such air so that it may be replaced thereafter by gas, comes in contact with atmospheric air and may therefore be thrown away, but in all successive operations, if the machine is not opened to atmospheric air, the liquid at no time comes in contact with atmospheric air, either in the measuring vessel or in the siphon itself, since at each operation the gas in the upper part of the measuring vessel E precedes the liquid into the siphon and, entering the same at the bottom it being heavier than air, drives the air therein out through the safety valve or vent a' .

As soon as the measured quantity of liquid has been driven out of the measuring vessel into the siphon, the outlet of the measuring vessel is closed by the valve e^2 , thereby stopping the further movement, either of gas or of air, and the machine then remains in its then condition until the filled siphon is removed and the hook h^5 is permitted to rise into engagement with the arm i' so that the parts are in position for the institution of another operation of filling as soon as the lever h is pressed down either by the hand of the operator or the application of the empty siphon to be filled.

It will be obvious that various changes in details of construction and arrangement can be made to suit different conditions of use. Thus, in place of valves D D' F F' of the type shown in detail in Figs. 7 and 8, there may be substituted rotary valves such as are shown in detail in Figs. 9, 10 and 11 and are shown in relation to the other parts of the machine in Fig. 12. In this construction the two valves D and D' are replaced by a single rotary valve D^x and the valves F and F' are replaced by a single rotary valve F^x. Both of the valves D^x and F^x may be mounted upon the shaft i^{2x} , mounted in suitable bearings on the main frame and provided with an arm i^{1x} for engagement with the latch

h^5 , and provided also with an arm i^{8x} for engagement with the piston k of the dash-pot K, all substantially as already described. The shaft i^{2x} may also be provided with a handle i^{0x} for manipulation by the operator. The latch h^5 , in this construction, is pivoted in fixed bearings h^{5x} and the arm e^{14x} is connected directly thereto. The arm e^{14x} has a finger e^{13x} which overlies the arm e^{11} connected to the float through the link e^{10} . The parts referred to and their connections are shown clearly in Figs. 9, 12 and 18 and operate substantially as already described.

The valves themselves, D^x and F^x, will now be described. The two valves are identical in construction and a description of the details of construction of one will answer for both. Mounted loosely on the shaft i^{2x} and supported in a fixed position by brackets d^x is a valve body which comprises a central body d^{1x} , chambered at its ends as at d^{2x} and d^{3x} and having threaded on each end a corresponding cap d^{4x} and d^{5x} . The central body is provided with a passage d^{6x} which affords communication, always open, between the pipe c^8 and the chamber d^{3x} ; with a passage d^{7x} which affords communication between the pipe c^6 and the chamber d^{2x} ; with a passage d^{8x} which affords communication between the chamber d^{3x} and the pipe c^9 , when the end of the passage d^{8x} is uncovered; and with a passage d^{9x} which affords communication between the two chambers d^{2x} and d^{3x} when its ends are uncovered. Against the opposite faces of the central body d^{1x} bear two valve disks d^{10x} which are keyed to the shaft i^{2x} so as to move therewith and may be pressed against the corresponding faces of the central body by springs d^{11x} . Each of the valve disks d^{10x} is provided also with a port d^{12x} adapted to register with the passage d^{9x} through the central body d^{1x} .

Since the passage d^{7x} is always open, the liquid from the supply vessel C may always flow to the chamber d^{2x} . When the parts are in the filling positions, as indicated in Fig. 18, with the arm i^{1x} engaged by the hook h^5 and held against the tendency of the spring k^1 in the dash-pot K to give the shaft i^{2x} a partial rotation clock-wise, the ports d^{12x} of the disks d^{10x} register with the passage d^{9x} so that the liquid may then flow from the chamber d^{2x} through the passage d^{9x} into the chamber d^{3x} and thence into the pipe c^8 and the measuring vessel E. When the hook h^5 is disengaged from the arm i^{1x} the spring in the dash-pot gives the shaft a partial rotation clock-wise which moves the port d^{12x} of one disk d^{10x} into registration with the passage d^{8x} , thereby placing the measuring vessel E in communication through the pipe c^8 , the chamber d^{3x} and the passage d^{8x} , in communication with the pipe c^9 and its discharge terminal c^x , whereby the liquid in the measuring vessel may then be

forced into the siphon A under the pressure of the gas in the top of the measuring vessel.

The construction of the gas valve F^{1x} is substantially identical with that of the liquid valve D^x , with the parts so arranged as to open an outlet for the gas from the measuring vessel to the siphon when the liquid is being admitted to the measuring vessel, and to direct the gas into the top of the measuring vessel when the liquid is being discharged from the measuring vessel into the siphon. It is unnecessary to enter into a detailed description of the valve and its connections so far as the operation of the gas valve without the addition of a syrup or extract adding device is concerned.

The machine shown in Fig. 12 is provided with a device for adding syrup or extract and while in such machine the rotary liquid valve D^x is constructed and connected as just described, the rotary gas valve F^{1x} has a special construction to suit the requirements of the case, such special construction being shown in Figs. 13 and 14 while the connections are shown clearly in Fig. 12. The syrup or extract is supplied from any suitable source through a pipe m to a measuring vessel M, suitably supported on the frame of the machine, as indicated in Fig. 12. As shown in Fig. 15 the measuring vessel M comprises preferably a central portion m' of glass and end caps m^2 and m^3 of metal. Adjustably suspended within the measuring vessel, by means of a lever m^4 pivoted in the upper cap m^2 , and a threaded rod m^5 , is a float m^6 . Also supported by the upper cap m^2 is a vent valve m^7 . The syrup or extract is admitted to and discharged from the vessel M through the connection m^8 at the bottom and a valve N which is controlled by the partial rotation of the shaft i^{2x} . The construction of the valve N may be identical with that of the valve D^x , as shown in detail in Figs. 9, 10 and 11, and therefore need not be further described herein. When the valve is in one position the liquid is permitted to flow from the pipe m into the vessel M through the connection m^8 and when the valve is in another position the liquid is permitted to flow from the vessel M through the pipe n^1 to and through the filling terminal c^x into the siphon in advance of the flow of the main body of the liquid from the measuring vessel E into the siphon, such precedence of flow of the syrup or extract not only permitting a thorough mixture of the main body of the liquid therewith to be effected as the main body of the liquid enters the siphon in the bottom of which the syrup or extract already stands, but causing the syrup or extract, which is usually more or less sticky, to be washed out thoroughly from the filling terminal c^x . The flow of the syrup or extract from the measuring vessel M is effected under gas

pressure, the gas being admitted to the top of the measuring vessel M by a pipe m^9 from the gas valve F^{1x} . Because of the conducting of the gas from the gas valve F^{1x} to the vessel M the construction of the valve F^{1x} , when the device for adding syrup or extract is added to the machine, is slightly different from that which answers the purpose when such device is not employed. The construction of such modified form of the gas valve F^{1x} is clearly shown in Figs. 13 and 14, the connections being shown in Fig. 12. The central body f^{1x} , supported in fixed position by brackets f^x and receiving loosely the shaft i^{2x} , is chambered at its ends, as at f^{2x} and f^{3x} and receives at its ends threaded caps f^{4x} and f^{5x} . A passage f^{0x} in the central body f^{1x} affords communication between the gas (supply) pipe c^{12} and chamber f^{3x} (see Figs. 5 and 12). A passage f^{7x} affords communication between the chamber f^{3x} and the gas supply pipe c^{11} . A passage f^{8x} affords communication between the chamber f^{2x} and the pipe m^9 by which the gas is conducted at the proper time to the top of the syrup vessel M. A passage f^{9x} affords communication between the pipe c^{13} and the chamber f^{2x} , so that the gas displaced in the measuring vessel E may be delivered to the measuring vessel M to drive out the syrup or extract therein.

Valve disks f^{10x} , held by springs f^{11x} against the corresponding faces of the central body f^{1x} , and each provided with a port f^{12x} for coöperation alternately with the passages f^{9x} and f^{7x} , respectively, are keyed on the shaft i^{2x} and the passages and ports are so positioned relatively to each other and to the ports and passages of the valves D^x and N that operations take place as follows: The liquid is first admitted to the measuring vessel E and the displaced air or gas therein is driven through the pipe c^{13} , the valve f^{1x} and the pipe m^9 into the measuring vessel M. The valve N at this time is in such position as to open communication between the measuring vessel M and the filling terminal c^x , so that the gas displaced from the measuring vessel E and entering the measuring vessel M drives out the syrup or extract from the measuring vessel M through the valve N and pipe n^1 into the siphon. When the predetermined quantity of liquid has entered the vessel E the float e^4 , through the connections e^5 e^7 and e^{10} shown in Fig. 1, and the connections e^{11} e^{12x} and e^{14x} shown in Fig. 18, disengages the hook h^5 from the arm i^{1x} and permits the shaft i^{2x} to receive a partial rotation clockwise under the influence of the spring k' of the dash-pot K. In the new position of the parts the valve D^x opens communication between the measuring vessel E and the filling terminal c^x , the valve F^{1x} opens communication between the gas conductor c^{11} and

the measuring vessel E and closes communication between the return pipe c^1 and the pipe m^3 leading into the measuring vessel M, thereby cutting off the gas pressure from the vessel M and permitting the vent valve m^7 to open, and the valve N cuts off communication between the measuring vessel M and the filling terminal c^8 and opens communication between the syrup pipe m and the measuring vessel M, thereby permitting the syrup or extract to enter the vessel M until the flow is cut off by the action of the float m^8 inclosing the vent valve m^7 . In these positions of the parts the liquid from the measuring vessel E flows into the siphon, washing out all of the syrup or extract from the filling terminal c^8 and making a thorough mixture with the syrup or extract in the siphon. The flow of the liquid ceases, as before, as soon as the vessel E is emptied and the parts remain in the positions then occupied until the attendant removes the filled siphon and replaces it with an empty siphon, at which time, grasping the handle i^9 , he restores the shaft i^2 , against the action of the spring k' of the dash-pot K, to its initial position in which it is held by reengagement of the latch k^5 with the arm i^1 . The successive operations are then repeated in the same way as before.

It will be seen that in each of the several constructions shown the flow of liquid to the receptacle to be filled will be cut off automatically through the action of the spring in the dash-pot when the predetermined quantity of liquid has been introduced into the receptacle and that in the form of the machine shown in Figs. 1-5 the flow of liquid through the filling pipe will also be cut off automatically, through the action of the spring in the dash-pot, whenever the siphon is removed from the machine so that there will then be no waste, either of gas or liquid.

It will be understood that various other modifications and changes in details of construction and arrangement, as required by different conditions of use, may be made without departing from the spirit of the invention, which is not limited to any particular construction and arrangement of parts.

I claim as my invention:—

1. In a filling machine, the combination of means to supply the liquid for filling, means to conduct the liquid to the receptacle to be filled, means to supply gas, means to conduct the gas to the receptacle to be filled, valves to permit or prevent the flow of liquid and gas to the receptacle, means under the control of the operator to open said valves, and independent automatically operated means to close the same valves.

2. In a filling machine, the combina-

tion of means to supply the liquid for filling, a vessel intermediate the supply and the receptacle to be filled, a filling terminal, pipe connections between the supply, the intermediate vessel and the filling terminal, valves to control said connections, means under the control of the operator to operate said valves to permit liquid to flow into the intermediate vessel, independent automatically actuated means to operate said valves to permit liquid to flow from the intermediate vessel to the filling terminal, and separate means to close the outlet of the intermediate vessel when the same is empty.

3. In a filling machine, the combination of means to supply the liquid for filling, a vessel intermediate the supply and the receptacle to be filled, a filling terminal, pipe connections between the supply, the intermediate vessel and the filling terminal, valves to control said connections, means under the control of the operator to operate said valves to permit liquid to flow into the intermediate vessel, automatically actuated means to operate said valves to permit liquid to flow from the intermediate vessel to the filling terminal, means to supply gas under pressure to said intermediate vessel to drive the liquid therein to the filling terminal, and independent means to close the liquid outlet of the intermediate vessel when the same is empty.

4. In a filling machine, the combination of means to supply the liquid for filling, a measuring vessel, a filling terminal, pipe connections between the supply, the measuring vessel and the filling terminal, a gas supply and independent pipe connections between the gas supply, the measuring vessel and the filling terminal, the measuring vessel and the filling terminal.

5. In a filling machine, the combination of means to supply the liquid for filling, a measuring vessel, a filling terminal, pipe connections between the supply, the measuring vessel and the filling terminal, a gas supply and pipe connections between the gas supply, the measuring vessel and the filling terminal, a valve to control said gas connections, whereby gas displaced by the liquid entering the measuring vessel is conducted to the filling terminal and gas is admitted to the measuring vessel to drive the liquid therefrom to the filling terminal.

6. In a filling machine, the combination of means to supply the liquid for filling, a measuring vessel, a filling terminal, pipe connections between the supply, the measuring vessel and the filling terminal, a gas supply and pipe connections between the gas supply, the measuring vessel and the filling terminal, a valve to control the gas connection between the supply and the measuring vessel, a valve to control the gas con-

nection between the measuring vessel and the filling terminal, and means to open and close said valves in alternation.

7. In a filling machine, the combination 5 of means to supply the liquid for filling, a measuring vessel, a filling terminal, pipe connections between the supply, the measuring vessel and the filling terminal, a gas supply and pipe connections between the 10 gas supply, the measuring vessel and the filling terminal, and a valve to close the liquid outlet of the measuring vessel when the same is empty.

8. In a filling machine, the combination 15 of means to supply the liquid for filling, a measuring vessel, a filling terminal, pipe connections between the supply, the measuring vessel and the filling terminal, a gas supply and pipe connections between the 20 gas supply, the measuring vessel and the filling terminal, and a float valve for the liquid outlet of the measuring vessel, holding the outlet open when there is liquid in the measuring vessel and closing the outlet when 25 the vessel is empty.

9. In a filling machine, the combination 30 of means to supply liquid for filling, an intermediate vessel, a filling terminal, two valves and connection from the supply to one of said valves, a connection from the other valve to the filling terminal, a common pipe connection between the bottom of the intermediate vessel and both of said valves, means to open and close said valves 35 in alternation, and a float valve controlling the outlet from the intermediate vessel to said last named connection.

10. In a filling machine, the combination 40 of means to supply liquid for filling, a measuring vessel, a filling terminal, pipe connections between the supply, the intermediate vessel and the filling terminal, a valve to control the connection between the supply and the intermediate vessel, a valve to 45 control the connection between the intermediate vessel and the filling terminal, means to open and close said valves in alternation, a spring and connections to shift said valve operating means in one direction, and a 50 hand operated lever to shift said operating means in the opposite direction.

11. In a filling machine, the combination 55 of means to supply liquid for filling, a measuring vessel, a filling terminal, pipe connections between the supply, the intermediate vessel and the filling terminal, a valve to control the connection between the supply and the intermediate vessel, a valve to control the connection between the intermediate 60 vessel and the filling terminal, means to open and close said valves in alternation, a spring and connections to shift said valve operating means in one direction, a counterweighted, hand operated lever with a latch

engaging said valve operating means to shift 65 the same in the opposite direction.

12. In a filling machine, the combination 70 of means to supply liquid for filling, a measuring vessel, a filling terminal, pipe connections between the supply, the intermediate vessel and the filling terminal, a valve to control the connection between the supply and the intermediate vessel, a valve to control the connection between the intermediate vessel and the filling terminal, means 75 to open and close said valves in alternation, a spring and connections to shift said valve operating means in one direction, a counterweighted, hand operated lever with a latch engaging said valve operating means 80 to shift the same in the opposite direction, and means to disengage said latch.

13. In a filling machine, the combination 85 of means to supply liquid for filling, a measuring vessel, a filling terminal, pipe connections between the supply, the intermediate vessel and the filling terminal, a valve to control the connection between the intermediate vessel and the filling terminal, means to open and close said valve in alternation, a spring and connections to shift said valve operating means in one direction, a counterweighted, hand operated lever with a latch engaging said valve operating means to shift the same in the opposite direction, a 90 float in the intermediate vessel and devices actuated thereby to disengage said latch.

14. In a filling machine, the combination 95 of an intermediate vessel, means to supply liquid thereto, a filling terminal, means to conduct liquid from the intermediate vessel to the filling terminal, means to supply gas to the intermediate vessel, a controlling valve therefor, means to conduct gas from the intermediate vessel to the filling terminal, a controlling valve therefor, and means to open and close said valves in alternation.

15. In a filling machine, the combination 100 of an intermediate vessel, means to supply liquid thereto, a filling terminal, means to conduct liquid from the intermediate vessel to the filling terminal, means to supply gas to the intermediate vessel, a controlling valve therefor, means to conduct gas from the intermediate vessel to the filling terminal, a controlling valve therefor, means to open and close said valves in alternation, a spring and connections to actuate said valve operating means in one direction, and 110 a hand operated lever to actuate said valve operating means in the opposite direction.

16. In a filling machine, the combination 115 of an intermediate vessel, means to supply liquid thereto, a filling terminal, means to conduct liquid from the intermediate vessel to the filling terminal, means to supply gas to the intermediate vessel, a controlling 120 valve therefor, means to open and close said valves in alternation, a spring and connections to actuate said valve operating means in one direction, and a hand operated lever to actuate said valve operating means in the opposite direction.

valve therefor, means to conduct gas from the intermediate vessel to the filling terminal, a controlling valve therefor, means to open and close said valves in alternation, a 5 spring and connections to actuate said valve operating means in one direction, and a hand operated lever with a latch to engage and operate said valve operating means in opposition to the spring.

16 17. In a filling machine, the combination of an intermediate vessel, means to supply liquid thereto, a filling terminal, means to conduct liquid from the intermediate vessel to the filling terminal, means to supply gas 15 to the intermediate vessel, a controlling valve therefor, means to conduct gas from the intermediate vessel to the filling terminal,

20
25
nal, a controlling valve therefor, means to open and close said valves in alternation, a spring and connections to actuate said valve operating means in one direction, and a hand operated lever with a latch to engage and operate said valve operating means in opposition to the spring, a float in the intermediate vessel, and devices the operation of which is initiated by the movement of the float to release said latch.

This specification signed and witnessed this 26th day of October A. D., 1914.

PHILIP J. SAULSON.
